(No Model.)

C. VAN HAAGEN.
HAMMER DIE FOR DRILL FORGING MACHINES.

No. 437,840.

Patented Oct. 7, 1890.

By his atty
UNITED STATES PATENT OFFICE.

CLAUS VAN HAAGEN, OF CHESTER, PENNSYLVANIA, ASSIGNOR TO THE
CHESTER TWIST DRILL AND TOOL COMPANY, OF SAME PLACE.

HAMMER-DIE FOR DRILL-FORGING MACHINES.

SPECIFICATION forming part of Letters Patent No. 437,840, dated October 7, 1890.

Application filed January 8, 1890. Serial No. 336,243. (No model.)

To all whom it may concern:

Be it known that I, CLAUS VAN HAAGEN, of Chester, in the county of Delaware and State of Pennsylvania, have invented an Improvement 5 in Hammer-Dies for Drill and Reamer Forging Machines, of which the following is a specification.

My invention has reference to hammer-dies employed in machines for forging drills and 10 reamers; and it consists in certain improvements, all of which are fully set forth in the following specification, and shown in the accompanying drawings, which form a part thereof.

15 My invention specifically relates to a suitable die adapted to be used in a machine for forging twist and other drills and reamers, and in which machine is employed two gripping-dies for holding the rod to be forged and two hammer-dies which operate in conjunction with the gripping-dies to forge in the groove, be it 20 spiral or straight.

25 The object of my invention is to produce a construction of hammer-die which shall be capable of withstanding the heavy duty and wear. In practice the hammer-die strikes the steel rod about four hundred times a minute and each time produces a decided deep forged portion of the ultimate groove.

30 In carrying out my invention I form the hammer-die with a flattened nose having its end rounded in all directions, and preferably with a striking part slightly askew to the body of the nose to correspond, in the case of 35 twist-drills, somewhat to the shape of the groove caused by its spiral or helical curve. When the die is to be used for straight drills and reamers, this askew portion is made parallel or in line with the body of the nose.

40 In making this hammer-die I cast it in a mold the lower part of which is iron, so that when the metal flows into the mold the nose portion is chilled and at the same time cast smooth and in condition for use. The shank 45 is cast in sand and is not so brittle as the nose.

45 In the drawings, Figure 1 is a perspective view of a set of dies, showing the relation of the hammer-dies to the gripping-dies. Fig. 50 2 is a perspective view of my improved ham-

mer-die. Fig. 3 is an end view of same, and Fig. 4 is a sectional elevation showing the mold in which the hammer-die is cast.

A B are two gripping-dies which have grooves forming the hole C for the rod when 55 the dies are placed together, and also the notches or grooves on the sides which form the oblique holes or slots D at right angles to the hole C when the said dies are placed together.

E E are the two hammer-dies, which are provided with the noses F, (best shown in Figs. 2 and 3,) which noses work through the slots or holes D between the dies A B. The gripping-dies may be also used to forge the 65 metal of the rod; but this construction is not claimed in this specification. If the dies are for use in forging straight drills and reamers, then the slots D are not oblique, as shown, but are in the same plane with the hole C. 70 The shank portions of the hammer-dies E are preferably of hard white cast-iron cast in sand I, while the nose portions F are of chilled cast-iron, which has been cast in the iron mold portion H, the sand I and iron portion H forming the mold J of the shape of the hammer-die. While the part H of the mold includes 75 all of the nose and shoulder, it is evident that the chill might be confined to the end of the nose, if desired. By making the chilled portion extend somewhat back provision for wear is made, and hence the die in operation lasts a long time compared with what would result if the chill included only the extreme point of the nose. The nose portion F has its ends 80 rounded in all directions, but also elongated, forming the part G and rounded ends f f. In the case of dies for twist-drills the part G is made askew, as more clearly shown by the shading in Fig. 3, to correspond to the peculiar 85 curve of the groove being forged, and so as to leave the proper cutting and trailing edges on the drill. The askew construction given to the end or point of the nose of the hammer-die is such as would correspond to the 90 peculiar curvature of the grooves in the twist-drill, which grooves not only have the peculiar cross-section, but also are formed helical, and necessitate the askew portion being 95 made to correspond to the resultant between 100

the helical and the shape due to the cross-section by said spiral grooves. The shank of the die E may be varied in shape, as desired.

Having now described my invention, what I claim as new, and desire to secure by Letters Patent, is—

1. As an article of manufacture, a hammer-die for drill and reamer forging machines, consisting of a body part or shank terminating in a flattened nose portion having its extreme end made with an elongated askew rounded portion, substantially as set out, and which nose portion is formed of chilled iron.

2. As an article of manufacture, a hammer-die for drill and reamer forging machines, consisting of a body or shank terminating in a flattened nose portion having its extreme end made with an elongated askew rounded portion, substantially as set out.

In testimony of which invention I have hereunto set my hand.

CLAUS VAN HAAGEN.
